Application May 24, 1940, Serial No. 337,067

82 Claims. (Cl. 12—1)

The present invention relates to shoe machines and methods and is herein illustrated in its application to machines and methods for use in assembling and shaping counter stiffeners and shoe uppers off the last.

In assembling counter stiffeners in lined uppers, it is the usual practice to apply adhesive to the counter stiffener and manually to insert the stiffener, which in most cases is a molded counter, between the lining and upper at the rear or heel portion of the shoe and then to apply pressure manually to the heel portion of the lining and upper in order to secure a permanent bonding of said parts. This method of assembling uppers and counters is slow and unreliable and when the assembled upper is lasted, the lasting stresses often cause the counter wings to move heightwise of the upper so that it is necessary to relocate the counter wings before the heel seat lasting operation.

It is an object of this invention to assemble counter stiffeners and shoe uppers off the last under conditions similar to those to which they will be subjected during the subsequent lasting operation and thereby to eliminate the tendency of the wing portions of the counter to move out of position when the assembled upper is lasted. To this end, the invention in one of its aspects relates to the method of assembling counters and uppers off the last, which comprises assembling a counter and an upper, stretching the assembled upper in a lengthwise direction and, while it is under lengthwise tension, exerting pulls on the lasting margin at selected side portions to set up in the upper stresses similar to lasting stresses, and shaping the heel end of the assembled upper while subjected to these stresses to bond the parts together under lasting conditions. In the practice of this method, as described herein, pulls are exerted on the lasting margin of the upper in the shank section to produce stresses similar to side lasting stresses and adjacent to the opposite ends of the tip line to duplicate pulling over stresses.

In another aspect thereof, the invention comprises immersing a counter in liquid cement and raising it to a draining position; then transferring the counter to a predetermined assembling position and positioning a lined upper about it, and, when the upper is properly positioned, holding the top margin thereof while wiping the rear part of the lining toward the counter flange.

It is another object of this invention to provide an improved machine for the practice of the above method. To this end, the illustrated ma-

chine is arranged to hold an assembled upper at selected points and is provided with an upper shaping form which is moved into and out of the supported upper to preshape the upper and to subject the upper to stresses similar to the stresses to which it is subjected in lasting. The holding means consists of grippers which are arranged to engage the lasting margin of the upper in the opposite shank portions and adjacent to the opposite ends of the tip line and to hold the upper against the stretch caused by the upper shaping form when it is moved into the upper.

Another feature of this invention relates to the mechanism for facilitating the assembling of a cemented counter and a lined upper. This mechanism is arranged to hold a cemented counter and a lined upper in determinate relation to each other, the upper being held about the heel end and in the shank and tip sections so that it is adequately supported, leaving both of the operator's hands free to smooth the lining over the inner side walls of the supported counter.

When assembling a counter and an upper, the operator frequently pulls the wings of a molded counter widely apart so that it will fit more readily into the pocket which the operator has to form between the upper and the lining with one hand while he inserts the counter with the other. When the counter wings are stretched in this manner, the counter loses its molded shape and the wings tend to remain wide apart with the result that they cannot perform their intended function of causing the heel end of the shoe to hug the foot of the wearer. With this in mind, it is a further object of this invention to provide mechanism for handling counters which will not pull or stretch molded counters out of shape during the cement applying and the assembling operations. To this end, the machine is provided with a counter cementing unit that includes a counter carrier for immersing a counter in cement, and with a counter transfer device which picks the cemented counter off the counter carrier and places it on the counter support. The counter transfer unit is arranged to lift the cemented counter off the counter carrier with a movement having rearward and heightwise components such that the counter carrier passes through the relatively wide foot opening in the counter and does not distort or spring apart the side walls of the counter. The counter is held in an upright position on the counter support so that the operator can use both hands in placing the lined upper about the counter.

In accordance with a further feature of this invention, the cementer counter is automatically clamped on the counter support as soon as it is placed thereon by the counter transfer device, and to this end a latched counter clamping member is automatically released by the counter transfer operating mechanism as the counter is placed on the counter support.

Invention is also to be recognized in the provision of an interlock between the side gripper operating mechanism and the clutch control which insures that the grippers are connected to the upper before the shaping form is moved into it, thus making sure that the desired stresses are set up in the upper by the shaping form; in an improved stretching device which pulls the marginal portion of the lining inwardly from the side walls of the counter beneath the downwardly moving heel end of the upper shaping form so that the heel of the form lays the lining smoothly against the counter flange; in the novel construction of the improved counter carrier and the arrangement of its operating mechanism by which a counter is held in a vertical position during the counter dipping operation, thus making it possible to apply cement to the side walls of the counter without moistening its sole attaching flange; and in the construction of the novel back seam gripping mechanism which tensions the heel end of an upper in a heightwise direction and holds it in that condition during the assembling and shaping operations.

These and other features of the invention will appear more fully from the following detailed description when read in connection with the accompanying drawings and will be pointed out in the appended claims.

In the drawings,

Fig. 24 is a perspective view showing the manner in which the upper and the lining are held by the grippers at the beginning of the lining-smoothing operation;

Fig. 25 is a view similar to Fig. 24 illustrating the lining-smoothing operation and also features of the back seam grippers; and

Fig. 26 is a rear view of the counter support in the cement pot.

Before commencing a detailed description of this machine, a brief outline will first be given of an upper and counter assembling and shaping operation as it is carried out on the machine. A molded counter is first placed flange up on the counter carrier in a cement pot 14 (Figs. 6 and 8) and is then manually dipped into the liquid cement which is of the quick-setting variety. After the counter is dipped, it is raised to a dripping position and the first part of the power cycle of the machine is initiated by the operator. This causes a counter transfer mechanism to pick the counter off the carrier in such manner as not to spring or bend the counter out of its molded shape and to transfer it flange down onto a U-shaped supporting member 58 located on the machine head where the counter is held during the subsequent assembling operation. The machine is then automatically stopped, whereupon the operator positions an upper around the counter and clamps gripping devices

to the top and bottom of the rear portion of the upper, and to selected marginal portions of the upper in the shank and forepart, and locates the toe of the upper with respect to a toe gripper which is subsequently operated. After attaching the gripping devices, the operator uses a forming tool or the like to smooth the lining against the counter (Fig. 25). The second part of the power cycle of the machine is then initiated and causes an upper shaping form 270 to move into the upper, stretching the same into approximately the shape it takes when lasted and at the same time pressing the lining against the counter, thereby causing the two to be firmly bonded together. As the form moves into the upper, the toe gripper grasps the toe end of the upper and exerts a longitudinal pull thereon which, together with the strains exerted by the side grippers, substantially duplicates in the upper the lasting strains so that the lining, counter and upper will be shaped about the heel end of the form 270 and firmly bonded together in their proper relative positions. The form remains in the upper a short interval after which it is automatically moved out of the upper and, as it moves away from the upper, a tripping mechanism is caused to release the grippers so that the assembled upper can be removed from the machine.

Referring now to Figs. 1 and 6, it will be seen that the machine frame comprises a hollow base 10 which encloses the treadle mechanism of the machine and a head 12 which forms a housing for the major part of the operating mechanism of the machine. Attached to the side of the head 12 (Fig. 3) is a cement pot 14 and means, which will now be described, for immersing a counter in the cement and handling it prior to the actual assembling operation.

Counter cementing unit

The counter cementing unit consists of the pot 14 which is open at the top and contains a suitable quick-setting liquid cement. The pot is located on the left side of the machine with its upper surface at approximately the level of the top of the machine head 12 and is fastened to the head by bolts 16 (Fig. 8) which pass through the side wall of the head and thence through hollow lugs 18 which extend out from the side of the pot 14.

Counters to be dipped in the cement are placed on a carrier which consists of a flat plate 20 (Fig. 20) shaped to fit within the inturned flanges of a molded counter and prevent it from tilting when immersed in the cement. The plate is provided with a depending flange 22 (Figs. 12 and 26) having a clip 24 which is adapted to engage the back of the counter and hold it in a vertical position with its inturned flanges positioned opposite to the sides of the plate 20. The plate is supported by a pair of spaced parallel links 26, 28 which are pivoted at one end to heightwise-spaced points on the depending flange 22. The lower link 28 is fastened at its other end to a pin 30 carried by a bolt 31 mounted in the end wall of the pot 14, while the other end of the upper link 26 is connected to a shaft 34 which is journaled above the pin 30 in the side walls of the pot. Due to the parallel arrangement of the links 26, 28, the plate 20 is held in a horizontal plane during the dipping operation so that the walls of the counter will be coated without getting cement on the inturned flanges.

The shaft 34 extends beyond the inner side of the pot 14 (Fig. 3) where it is connected to

10 a dipping handle 36 having a depending arm 40. The upper position of the counter carrier (Fig. 12) is determined by a stop screw 42 which is located behind the arm 40 where it is threaded in a lug 43 that projects out from the side of the pot. The arm is normally held against the screw by a tension spring 38 which is connected at one end to the arm 40 and at its other end to a rearwardly-located pin 39 that juts out from the side wall of the pot.

Counter transfer mechanism

When counters are molded, their edges are curved inwardly to form a reduced opening which will cause the heel portion of a shoe to hug the foot of the wearer. During the assembling operation, it is important that the counters be handled in such manner that the side walls are not bent or opened to a degree which will cause the counters to lose their molded shape. To this end, it is contemplated that when an operator places a counter on the cement pot support, he will present the counter, flange up, to the plate 20 with the wide portion of the front opening of the counter opposite the end of the plate 20. The operator will then move the counter forwardly until the wider opening in the heel portion of the counter is reached and then downwardly to engage its rear wall with the clip 24 and to bring the counter flange into alignment with the plate 20. After the counter has been dipped in the cement and returned to the dipping position shown in Fig. 8, it is removed from the support by a counter transfer mechanism which reverses the movements of the counter when being placed on the support. The counter transfer mechanism is operated by the machine through mechanism which will hereinafter be described, the machine operation being initiated by the manual operation of a clutch lever 274 (Fig. 1).

The counter transfer mechanism comprises a pair of levers 50 and 52 (Fig. 3) which are located rearwardly of the cement pot counter support and are provided with counter gripping means consisting of a pair of bars 66 and 68 which are pivoted respectively on the ends of the levers and are each provided with two transversely-extending counter-gripping needles 70. The levers 50, 52 are pivotally mounted one end of a crank arm 54 and are caused to move in unison toward and away from each other by intermeshing gears 62 and 64 formed on their adjacent ends. The other end of the crank arm 54 is provided with a collar 55 which is clamped to a hollow shaft 56 that extends longitudinally of the machine midway between the cement pot counter support and a U-shaped counter support 58 (Figs. 8 and 20) mounted on the top of the head 12.

The counter gripping means is caused to take hold of and release a counter by the action of a link 82 (Fig. 3) which is connected to the lever 52 and rotates the same when moved forwardly or rearwardly with respect to the arm 54 by the movement of a longitudinally reciprocating rod 84, as hereinafter described, rotation of the lever 52 causing a corresponding movement of the lever 50 through the action of the gears 62, 64. After the counter gripping means takes hold of a counter, the shaft 56 is rotated to transfer the counter to the U-shaped support 58, the rotation of the shaft being effected by the action of a segmental gear 76 on an elongated pinion 74 which is fastened to the rear end of the shaft 56. When the arm 54 is rotated, the link 82 is caused to

rotate with it by the action of a pair of spaced arms 78 and 80 (Fig. 20) which project out from the blank portion of the pinion 74 and receive the rear portion of the link between them.

The shaft 56 is mounted in a bearing 60 which is shorter than the distance between the adjacent ends of the collar 55 and the pinion 74 (Fig. 3) so that the shaft 56 can be moved rearwardly in the bearing during the early part of the counter transferring operation to move the wider part of the counter opening at the front of the counter opposite the plate 20 as the counter is raised from the carrier by the arm 54 and thereby avoid opening the counter wings an appreciable amount when the counter is moved upwardly past the plate. The teeth on the pinion 74 are of such length that they will remain in mesh with the teeth in the gear segment 76 at all times during the axial movement of the shaft 56.

The hollow shaft 56 is moved back and forth in the bearing 60 by the rod 84 (Figs. 3 and 9) which is mounted in the hollow shaft and is frictionally coupled with the shaft by a spring-pressed bar 86 which is seated in a groove formed in the rod. The bar is forced against the inner wall of the shaft 56 by a long bowed spring 88 (Fig. 3) which is confined between the back of the bar 86 and the bottom of the groove formed in the rod. Thus, when the rod 84 is reciprocated, the friction between the bar 86 and the inner wall of the shaft 56 will cause the shaft to move with the rod until either the sleeve 55 or the pinion 74 strikes an end of the bearing 60 whereupon the shaft 56 will stop and the rod 84 will continue its movement. The mechanism which reciprocates the rod 84 is arranged to continue the movement of the rod for a short distance after the movement of the shaft 56 has been stopped by the bearing 60 and this additional movement of the rod is utilized to open and close the counter gripping means. The control of the counter gripping means is effected through the link 82 which is connected to the rod 84 by a plate 87 (Figs. 3 and 23) attached to an arm 85 formed on the rearwardly projecting end of the rod 84.

The rod 84 and the pinion 74 are operated by a cam 92 (Figs. 11 and 16) mounted on a shaft 94 which is coupled to the main drive shaft of the machine by a clutch 96 (Fig. 1). The cam 92 is located outside of the head 12 adjacent to the cement pot 14 and controls the pinion 74 through a lever 98 which is connected at its upper end to the pinion 74 by a gear segment 76 and at its lower end to the cam by a follower roll 95 which travels in a peripheral cam groove 93. The lever 98 is pivoted intermediate its ends on a bolt 99 which extends longitudinally of the head 12 and is supported by a lug 97 that projects out from the side wall of the head. The cam 92 controls the movement of the rod 84 through a linkage system consisting of a bell crank lever 100 one arm of which is connected to the rod 84 by a link 102 and the other arm of which is connected by a link 104 to a cam follower 103 which travels in a cam groove 105 (Figs. 11 and 18) formed in the side of the cam 92 adjacent to the side wall of the head 12. The cam follower 103 is also connected to one end of an arm 106, the other end of which is pivoted on a transversely extending bolt 108 (Figs. 18 and 19) mounted in the side wall of the head 12 beneath the pivot of the lever 100.

A better understanding of the counter transfer mechanism can probably be had from a descrip-

tion of its operation. At the beginning of an assembling operation, that is, when a counter is placed on the cement pot counter carrier, the arm 54 is positioned a slight distance rearwardly of the position shown in Fig. 3, and the clamping levers 50, 52 are spaced wider apart than they are shown in that figure. When the counter is ready to be taken off the support, the operator initiates the first machine operation by moving the clutch lever 274 to the right, as viewed in Fig. 1. This causes the rod 84 to move to the left, as viewed in Fig. 3, carrying the shaft 56 and arm 54 with it until the pinion 74 strikes the bearing 60 after which continued movement of the link 82 causes the levers 52 and 50, through the action of the gears 62, 64, to move inwardly toward each other until the needles 70 grip the sides of the counter. Axial movement of the rod 84 is then stopped for a moment and the shaft 56 is rotated to release the counter from the latch 24 (Fig. 26) and raise the inturned counter flanges above the plate 20. As the counter flanges move above the plate 20, the rod 84 is moved sharply to the right, as viewed in Fig. 3, partly to withdraw the counter from the support while the plate 20 is in the relatively wide mid-section of the counter. During this movement of the rod 84, the shaft 56 continues to rotate but at a slower rate and concomitantly raises and tilts the counter so that the counter assumes an angular relation with respect to the plate 20. After the counter assumes a desired angular relation with respect to the plate 20, the rate of the rearward movement of the rod 84 is reduced. Continued rotation of the shaft 56 causes the plate 20 to pass through the top and front counter openings thus effecting the withdrawal of the counter without appreciably springing its side walls. The gear segment 76 continues to rotate the shaft 56 until the counter is seated flange downward on the U-shaped support 58 (Fig. 20). When the counter is seated on the support 58, a clamping finger 90 (Figs. 18 and 24) is moved, in a manner which will hereinafter be described, to a position where it clamps the inturned counter flange against the support 58. As the counter is clamped against the support 58 by the finger 90, the arm 54 strikes the bearing 60 stopping the rearward movement of the shaft 56. The rod 84 continues to move to the right after the arm 54 stops, thereby causing the link 82 to move rearwardly relatively to the arm 54 and move the clamping levers 50, 52 away from each other sufficiently to release the counter. When this is done, the gear segment 76 reverses the direction of its movement and moves the arm 54 backward to its position at the beginning of the operation. This position is opposite to the full line position of the arm 54 shown in Fig. 20 and it will be seen that that position is rearwardly of the dotted position of the arm 54 which is the location of the arm when the counter is placed on the support 58.

Upper assembling

After a counter has been clamped upon the support 58, the operator takes a lined upper in his hand, separates the quarter lining from the upper, and slips the upper over the counter, the top of the head 12 and the back side of the support 58 forming a guide for positioning the heel portion of the upper. A number of grippers are then attached to the upper, the grippers consisting of a pair of heightwise-spaced back seam grippers which engage the top and bottom of the

upper along the back seam and stretch the heel end of the upper in a heightwise direction; a pair of widthwise-spaced grippers which grasp the lasting margin in the inside and outside shank portions of the upper; a second pair of widthwise-spaced grippers which grasp the lasting margin at opposite ends of the tip line; and a gripper which grasps the lasting margin of the upper at the tip end of the toe portion. In addition to supporting the upper in determinate relation to the counter while the lining is being smoothed against the counter, the side grippers cause lasting stresses to be set up in the upper when the upper shaping form stretches the upper as will subsequently be fully described.

The back seam grippers consist of a bar 120 (Figs. 5 and 18) having an enlarged head which is arranged to clamp the lasting margin of the upper against the back side of the support 58, and a pair of gripping jaws 122, 124 which grip the top portion of the upper at the back seam. The bar 120 is pivoted to an arm 126 of a hand lever 128, the bar 120 and the arm 126 forming a toggle which, when straightened, clamps the upper against the support 58 and holds the lever 128 in the upright position shown in Fig. 16. The lever 128 is pivoted on a pin 130 (Fig. 5) which is mounted in openings formed in ears 132, 134 that project from the top of the casing 12. The upper jaws 122, 124 which take hold of the top portion of the upper are carried by an assembly which is arranged to be rocked back and forth between an inoperative position shown in Fig. 18 and an operative position shown in Fig. 16. The jaw 124 is formed on the forward end of a channel-shaped member 136 that is swingably connected to the top of the casing 12 by a pair of supporting members 138 (Figs. 5 and 18) which are pivoted at their upper ends to the member 136 and are connected at their lower ends by screws 140 to a pair of apertured ears 142 which project up from the top of the casing. The jaw 122 constitutes the forward face of a block 144 which is slidably mounted in the groove formed on the under surface of the channel-shaped member 136 and is held in that groove by a headed screw 148 which extends downwardly through a slot 150 formed in the web of the member 136 and into threaded engagement with the block 144. The block is moved back and forth in the groove by a toggle consisting of a link 154 which is connected at its forward end to the block and at its rear end to a lever 152 pivoted to the rear end portion of the member 136. The jaw 122 is urged toward the jaw 124 by a spring 156 (Fig. 5) which surrounds the pin 130 and has one end thereof hooked beneath a stud 158 on a rearwardly extending arm 160 (Fig. 25) that is loosely mounted on the pin 130. The arm 160 is connected to the lever 152 by a pair of links 162 so that the upward pressure exerted by the spring upon the arm is transmitted to the lever and tends to straighten the toggle and thereby force the block 144 toward the jaw 124. The spring 156 also tends to lift the front end of the upper gripper. This is due to the fact that the other end of the spring 156 is hooked beneath a stud 164 (Fig. 5) projecting from a forwardly extending arm 166 which is also journaled on the pin 130, the arm 166 in turn being connected by a link 168 to the forward end of the member 136.

When the jaws 122, 124 grasp the upper, the arm 166 is urged upwardly by the action of the forwardly extending end of the spring 156. Up-

ward movement of the arm 166 causes a corresponding upward movement of the link 168 which lifts the front end of the member 136 about its point of connection with the links 138 as a center; the links 138, being anchored to the top of the head 12, act as a fulcrum for the member 136. The upward movement of the front end of the member carries the jaws 122, 124 upwardly, thereby stretching the back part of the upper in a heightwise direction. The back portion of the upper is positively held under tension while the rear portion of the form 270 downwipes the lining by a detent comprising a one-way clutch which permits the arm 166 to move upwardly to tension the upper but prevents its downward movement. The one-way clutch consists of a segment 170 (Figs. 5 and 25) which projects rearwardly from the hub of the arm 166, and a brake arm 172 which is in alignment with the segment 170 and is pivoted on a rearwardly-located pin 174. The arm 172 engages the face of the segment 170 below the line of centers extending between the pins 130 and 174 and is urged upwardly by a spring 176 (Figs. 18 and 25) that engages the under side of an arm 178 which projects from the hub of the brake arm 172. When the toggle 152, 154 is broken (Fig. 18), the links 162 are displaced downwardly from the member 136 and as the arm 178 engages the lower ends of these links (Figs. 5 and 25), it will also be displaced downwardly a sufficient distance to carry the brake arm 172 out of engagement with the face of the segment 170 whereupon the upper gripper assembly can be moved freely back and forth about the pivot pin 130. When the toggle is broken at the end of an assembling operation, a spring-pressed latch 155 mounted on the rear end of the member 136 snaps over the tail end of the lever 152 and holds the toggle in its broken position and the one-way clutch in an inoperative condition until the operator releases the latch to clamp the upper gripper to an upper during the next assembling operation.

The operation of the back seam grippers will now be described. Assuming that an upper has been placed in the position shown in Fig. 18, the operator rotates the lever 128 in a counter-clockwise direction to straighten the toggle formed by the arm 126 and the bar 120, thus clamping the margin of the upper against the back face of the support 58. The operator then grasps the member 136 and moves the whole upper gripper assembly comprising the member 136 and the links 138, 162 and 168 forwardly until the open jaws 122, 124 lie above the back portion of the upper when he presses down upon the member 136, causing the arm 160, 166 to move downwardly about the pivot pin 130 and swing the member 136 downwardly about its pivotal connection to the members 138 until the jaws 122, 124 are in position on opposite sides of the top portion of the upper. He then releases the latch 155 allowing the spring 156 (Fig. 5) to straighten the toggles 152, 154 and cause the jaws 122, 124 to grip the upper between them whereupon he removes his hand from the member 136. Upon release of the latch 155, upward movement of the arm 160 and links 162 allows the arm 178, which underlies the arm 160, to move upwardly under the urging of the spring 176 and bring the face of the brake arm 172 into one-way locking engagement with the face of the segment 170. This locking engagement prevents further counterclockwise movement of the segment 170 and arm 166 which is connected

thereto and as the arm 166 is connected to the forward end of the member 136, it also prevents the upper gripping jaws from moving downwardly. However, if there is any slack in the back portion of the upper, the spring 156 which tends to raise the arm 166 will rotate that arm in a clockwise direction until the back of the upper is taut, rotation of the arm 166 in that direction being permitted by the one-way clutch.

After the back seam has been gripped by the back seam grippers, the operator then places the lasting margin of the inner and outer shank portions of the upper between the jaws of a pair of widthwise-spaced grippers 182, 184 (Fig. 3) located on opposite sides of the upper, and the jaws of the grippers are then closed against the upper by treadling a lever 188 (Fig. 2). As the construction of the different side grippers is the same, only the typical gripper shown in Fig. 10 will be described in detail, and like numerals will be given to the similar parts of the different grippers. Referring to Fig. 10, the gripper comprises a cylindrical sleeve 190 which is freely mounted on a rod that is supported by the side walls of the head 12. Extending upwardly from the sleeve 190 is a plate 194 having an inclined slot 198 formed in its upper portion and a jaw 196 on its free end. Pivotaly connected to the plate 194 by a pin 199 is a second plate 200 having a jaw 202 formed on its end opposite the jaw 196 and a straight slot 204 in its lower portion opposite the area in which the inclined slot 198 is formed in the plate 194. The jaw 202 is moved toward and from the jaw 196 by a pin 206 which extends through the slots 198 and 204 and is connected at its ends to downwardly extending links 208 and 210 (Figs. 1 and 16) located on opposite sides of the plate 198. The lower ends of the links 208, 210 are connected by pins 211 to the arms of a forked operating lever 212, one end of which is pivoted at 214 to the sleeve 190 and the other end connected to a treadle.

The shank grippers 182, 184 are pivoted on a rod 192 (Fig. 16) which is mounted in aligned openings in the side walls of the head 12, the gripper-operating levers 212 projecting out through openings formed in the side walls adjacent to the bearings for the rod 192. The projecting ends of the lever 212 are connected by links 216 to the projecting ends of a yoke 218 which extend outwardly through openings 220 in the casing 10. The yoke is connected intermediate its ends to the upper end of a link 222, the lower end of which is connected through a relief spring 228 and a lever 230 to the treadle 188.

The connection between the lower end of the link 222 and the lever 230 consists of a sleeve 224 which is slidably mounted on the link between a collar 226 and the relief spring 228, the spring being held on the link by nuts 229. The relief spring 228 protects the gripper mechanism from excessive treadle pressure by permitting the sleeve 224 to move downward relatively to the link 222 after the gripper jaws have been pressed against the work. The sleeve 224 is connected to the forward end of the lever 230 which is in turn pivoted intermediate its ends on a shaft 232 that also supports the treadle 188. The lever 230 is connected with the treadle 188 by a laterally extending arm 234 (Fig. 2) which underlies the treadle 188 and is held against the treadle by a spring 433 (Fig. 1) when the gripper jaws are released. When the lever 230 is de-

pressed to close the gripper jaws, it is held in that position by a spring-biased latch 265 which snaps beneath a finger 235 formed on the rear end of the lever. After the lever 230 is latched, 5 the operator releases the treadle 188 which is returned to its upper position by a spring 434 (Fig. 6). When the latch 265 is released, the spring 433 raises the front end of the lever 230, thereby effecting the opening of the jaws of the grippers 182, 184.

Having clamped the grippers 182, 184 to the shank portion of the upper, the operator next places the lasting margin at the opposite ends of the tip line between a pair of widthwise-spaced 15 grippers 236, 238 (Figs. 3 and 4) and then closes the jaws of those grippers by depressing a treadle 240 (Fig. 1). The grippers 236, 238 are pivoted on a rod 242 journaled in the side walls of the head at the front end of the machine. The 20 operating levers 212 of the grippers 236, 238 are connected to the treadle 240 by a pair of links 244 (Fig. 6) which are pivoted at their upper ends, respectively, to the ends of the lever 212 and at their lower ends to a yoke 246, the yoke in turn 25 being connected intermediate its ends to the upper end of a rod 248, the lower end of which is connected to a lever 252 by a sleeve 250 which is 30 slidable on the lower end of the rod between a collar 256 and a relief spring 254. The lever 252 is journaled on a shaft 258 which also serves as a mounting for the treadle 240 (Fig. 2) and is connected to the treadle by a laterally extending arm 241. The jaws of the grippers 236, 238 are held shut by a spring-biased latch 264 (Fig. 1) 35 which snaps beneath a finger 260 formed on the rear end of the lever 252 when that lever is depressed by the treadle 240 so that the treadle can then be released and returned to its upper position by a spring 430. When the latch 265 is moved out from under the finger 260 by a release mechanism which will presently be described, a spring 432 connected to the forward end of the lever 252 raises that lever and thereby 40 effects the opening of the jaws of the grippers 236, 238.

After depressing the treadle 240, the operator next places the tip end of the toe portion of the upper between the open jaws of the toe gripper 266 (Fig. 18) which does not take hold of the 50 upper until the next machine operation when the upper shaping form 270 is moved upwardly into the upper. The toe gripper 266 consists of a lower jaw 340 (Fig. 18) formed on the upper end of an arm 350 which is pivoted on a transversely extending rod 351 supported by the side walls of the head 12. The upper jaw 341 is formed by the rearwardly extending arm of a bell crank lever 346 which is pivoted on the upper end of the arm 350, the lower arm of the bell crank lever being connected by a pin-and-slot connection to the upper end of a lever 344 which is in turn pivoted intermediate its ends on the rod 351. The forward edge of the arm 350 has formed thereon an apertured boss in which is mounted a cross arm 348 (Fig. 3) which is connected at its ends, respectively, to the grippers 236, 238 by springs 352, 354. When the toe gripper 266 is clamped against the upper and is moved forwardly to exert a longitudinal pull on the upper by a mechanism which will be hereinafter described, the springs 352, 354 exert a forward pull of the tip line grippers 236, 238, causing them to exert a forward pull on the side portions of the upper.

When all of the grippers are properly adjusted,

the operator wipes the lining against the counter with an appropriate tool such as the blunt-ended blade 272 shown in Fig. 25. As the lining is smoothed, the extra material in the bottom portion of the lining along the wings of the counter will lie smoothly upon the upper surface of the counter flange, and the excess material will form gathers in the back portion of the counter about the enlarged head of the clamping finger 90, in the manner shown in Fig. 25. Elimination of gathers over the counter flange in the wing portions of the counter does away with the possibility of creases being formed in the lining in that area during the subsequent heel shaping operation. The wiping action of the tool also causes the adhesive to flow downwardly from the side walls of the counter and coat the top of the counter flange, with the result that the portion of the lining which overlies the flange will be bonded to it when the two are pressed together by the heel end of the form 270.

Upper stretching and shaping

After the lining is smoothed against the counter, the operator moves the clutch operating lever 274 (Fig. 1) to the right, connecting the clutch 96 and causing the operating mechanism of the machine to go through the second part of the power cycle. These operations cause the upper shaping form 270 to move up heel end first into the upper and as the form moves upwardly, the jaws of the gripper 266 are closed about the toe end of the upper and the gripper is moved to the left, as viewed in Fig. 18. Movement of the gripper in that direction pulls the upper taut longitudinally against the heel end of the form and also causes a corresponding movement of the tip line grippers 236, 238, which sets up a longitudinal pull on the sides of the upper. The upward movement of the form 270 stretches the upper in a heightwise direction, and the instep portion 273 of the form under the influence of a spring 275 supplements that action in the instep portion of the upper, with the result that the pull exerted by the tip line grippers 236, 238 duplicates pulling over stresses, and the pull from the shank grippers 182, 184 duplicates the side lasting stresses. As the form is moved into the upper, the heel end of the form is swung rearwardly and downwardly until it is stopped by the support 58. Shortly before the heel end of the form reaches the support, it contacts the lower portion of the lining and wipes the lining downwardly as it moves toward the support. The pull exerted on the upper by the grippers causes the heel part of the upper to lie tightly against the heel end of the form, thereby shaping the heel end of the upper about the form and firmly bonding the lining, counter, and upper together in proper relation to one another, while the pressure of the bottom of the form against the underlying lining margin and counter flange firmly bonds the two together. After a short interval, sufficient to permit the quick-setting cement to form an initial bond between the lining, counter, and upper, the form is moved out of the upper and all of the grippers are automatically released.

The mechanism for effecting the above operations consists of a cam 280 which is located within the head 12 and is keyed to the driven shaft 94 (Fig. 11). The heightwise movement of the form 270 (Figs. 16 and 18) is jointly controlled by cam grooves 282, 404 formed, respectively, in the opposite side faces of the cam 280,

the heightwise movement of the forepart of the form being controlled by the groove 282 and effected through a linkage system consisting of a link 284, lever 286, and link 292. The link 284 is pivoted at its forward end to the lower portion of the lever 286 and at its rearward end to a cam follower 287 (Fig. 17) which travels in the groove 282. The cam follower is also connected to the upper end of an arm 288, the lower end of which is journaled on a rod 290 (Fig. 16) fastened to the side walls of the head 12 below the cam 280. The lever 286 is pivoted intermediate its end on a bolt 291 which projects inwardly from the side wall of the head 12 and is connected at its upper end to the link 292 which is in turn connected to the upper shaping form 270 by a pin 294. The lever 286 and the link 292 form a toggle which, as it is straightened, raises the forward end of the form 270 to the position shown in Fig. 16 and finally forces the heel end of the form against the counter support 58. As the forepart of the form 270 is raised through the action of the cam groove 282 on its controlled linkage, the form is moved rearwardly by another linkage system which is controlled by the cam groove 404 formed in the opposite side of the cam 280. This linkage system consists of a lever 400, link 406 and a pair of swingably mounted arms 296, 298 (Figs. 18 and 22) which are connected at their upper ends to the form. The lever 400 is pivoted in its mid-section on a pin 401 (Figs. 11 and 16) and carries at its lower end a cam follower 402 which travels in the cam groove 404. The lower ends of the arms 296, 298 (Fig. 22) are journaled upon a pair of studs 300, 302 which are mounted in bosses 304 that extend inwardly from the side walls of the head 12, while the upper ends of the arms are connected with the heel portion of the form 270 by a pin 306.

As the heel portion of the form 270 approaches the counter support 58, the counter clamping finger 90 is withdrawn from engagement with the counter flange and moved forwardly to the position shown in Fig. 16 where it lies within an opening 271 formed in the heel portion of the form and thus permits the unobstructed movement of the heel portion of the form down into contact with the material lying upon the support 58. Withdrawal of the clamping finger 90 is caused by the operation of a linkage system which is controlled by the lever 286 and is rendered effective to withdraw the finger when the lever is moved in a counterclockwise direction to raise the form. The linkage system consists of a link 308 (Figs. 16 and 18) which is connected at one end to the upper portion of the lever 286 and at its other end to the arm 310 of a cam 312 which is mounted on a transversely extending rod 322 supported by the side walls of the head 12. The face of the cam 312 engages a roller 314 on a slide bar 316 which is urged toward the rear of the head 12, or to the right as viewed in Fig. 18, by a spring 320 which is connected at one end to the bar 316 and at its other end to the rear wall of the head. The rod 322 passes through an elongated slot 324 formed in the rear portion of the bar 316, the slot permitting forward or rearward movement of the bar with respect to the cam as different portions of the cam act on the roller 314 and cause the displacement of the bar. The forward end of the bar 316 is connected by a pin 326 to the upper end of a supporting arm 328 which is pivoted on a rod 330. Also pivotally mounted on

the rod 330 adjoining the arm 328 is a rearwardly extending link 332 which is connected to the lower end of the clamping finger 90 by a screw 334. The portion of the clamping finger 90 which lies opposite to the bar 316 is provided with a laterally extending pin 338 formed in the forward end of the bar 316, the pin being urged toward the rear end of the slot by a spring 340 which is connected at one end to the finger 90 and at its other end to the rear end of the bar 316. When the upper shaping form 270 is raised, the bar 316 is moved in a forward direction from its position shown in Fig. 18. The initial portion of this movement causes the pin 338 to ride upwardly in the slot 336, thereby lifting the finger 90 from the counter flange, and continued movement of the bar after the pin contacts the rear wall of the slot carries the finger with it to the position shown in Fig. 16 where it is clear of the rear wall of the form 270.

Located rearwardly of the bar 316 is a latch 360 which holds the finger 90 in its inoperative position shown in Fig. 16 until the appropriate time during the counter transfer operation when a raised portion 356 of the cam 280 moves the latch to an inoperative position, thereby releasing the finger and permitting it to clamp the counter flange against the counter support. The latch consists of a forwardly extending arm 364, which engages the rear end of the bar 316, and a depending arm 361, which carries a roller 358 that engages the peripheral face of the cam 280. During the counter transfer operation, the raised portion 356 moves beneath the roller 358, causing the latch to move sufficiently in a counterclockwise direction to carry the arm 364 out of engagement with the rear face of the bar 316, thereby permitting the spring 320 to move the slide 316 to the right, as seen in Fig. 16, and swing the finger 90 against the flange of a counter on the support 58. During the subsequent form-raising operation, when the bar 316 is moved forwardly, the raised portion 356 passes from beneath the roller 358, permitting a spring 362 located back of the arm 361 to move the latch in a clockwise direction until the finger engages the rear end of the bar and latches the finger in its inoperative position.

As the form 270 is raised, the lever 286 acting through a spring 342, causes the toe gripper 266 to take hold of the upper and exert a lengthwise pull on the same, the spring 342 being connected at one end to the lower arm of the lever 286 (Fig. 18), which moves rearwardly during the upper-raising operation, and at its other end to the lower end of the lever 344. When the lower arm of the lever 286 moves rearwardly, the pull of the spring 342 causes the lever 344 to rotate in a counterclockwise direction, as viewed in Fig. 18, and the upper jaw 347 to move against the lower jaw 349. After the jaws 347, 349 grasp the upper between them, the toe gripper assembly, consisting of the upper end of the lever 344, the lever 346, and the arm 350, moves as a unit to the left, as viewed in Fig. 16, and exerts a lengthwise pull on the upper. Movement of the arm 350 to the left pulls the tip line grippers in that direction through the action of the springs 352, 354, thus tensioning the sides of the upper. The shank grippers 182, 184, being freely mounted on the rod 192, will move forwardly to adjust themselves to whatever forward displacement there is in the shank portion of the upper 75

caused by the lengthwise pull imparted to it by the toe and tip-line grippers.

As the form 270 moves up into the upper, the lower portion of the lining adjacent the side walls of the counter is stretched inwardly away from the side walls, in a manner which will now be described, so that the margin of the heel seat face of the form, as it moves downwardly, presses against the taut lining and lays it smoothly upon the inturned counter flange. When the operator smooths the lining against the inner walls of the counter, the margin of the lining will lie over the inner ends of a pair of transverse levers 368, 370 (Fig. 21) which are positioned opposite to the side walls of the counter (Fig. 3). The levers 368, 370 are pivoted, respectively, on pins 372, 374 mounted on ears on the top of the head 12 adjacent to the side walls, the outer arms of the levers projecting beyond the sides of the head and being urged downwardly by springs 376, while the inner arms of the levers extend toward the center of the head and are substantially V-shaped so that they pass beneath the flange of a counter on the support 58 (Fig. 20). As the heel end of the form 270 is moved into the heel end of the upper, a bar 366 (Fig. 18) moves ahead of the heel end of the form and grips the lining between it and the ends of the levers 368, 370, as shown in Fig. 21. As the heel portion of the form continues to move toward the support 58, the bar 366 continues its downward movement, carrying the levers with it, and thus pulls the margin of the lining downwardly, thereby causing the bottom portion of the lining to stretch inwardly from the side walls of the counter over the counter flange. While the lining is stretched in this manner, the margin of the heel seat face of the form 270 moves into engagement with the counter flange and as it does, it pulls the lining inwardly from the levers 368, 370 and the bar 366 and lays it smoothly against the counter flange as is indicated in Fig. 22.

The bar 366 is integral with the upper end of a slotted plate 390 (Fig. 21) which is located between the arms 296, 298 (Fig. 22) and is coupled with the arms by a pair of heightwise-spaced pin-and-slot connections which permit the plate to move relatively to the arms. The connections are formed by a pair of slots 392, 394 in the plate 390 (Fig. 18), the slot 394 receiving the pivot pin 306 that connects the arms 296, 298 to the form (Fig. 22) and the slot 392 receiving a pin 396 extending between the arms 296, 298. The lower end of the plate 390 is connected by a pair of links 384, 386 (Figs. 18 and 21) to the rearward end of an offset arm 378, the forward end of which is pivoted on a rod 380. The upper surface of the arm 378 engages beneath a roller 382 on the lever 286, the location of the offset in the arm being such that when the lever is rotated to raise the form, the roller 382 passes over the offset and forces the arm downwardly, thereby causing the bar 366 to move downwardly and stretch the lining.

After a short dwell in the position shown in Fig. 16, the form 270 is moved back to the position shown in Fig. 18 and as it is moved back, the back seam grippers and the side grippers are automatically released by mechanism which will now be described. The back seam grippers are released by a trip 408 which is pivoted on the link 406 adjacent to a depending finger 410 on the lever 128. When the link 406 is moved to the right during the form raising operation, the trip 408 snaps beneath the finger 410 as it moves

to the position shown in Fig. 16. Upon movement of the form downwardly from the upper, the link 406 is moved to the left, causing the end of the trip 408 to strike against the flat side face of the finger 410 (Fig. 14) and rotate the lever 128 in a clockwise direction which raises the arm 126, breaking the toggle 120, 126 and releasing the lower back seam gripper, and also lowers a rearwardly extending arm 412 which overlies the pin 158 on the arm 160. Downward movement of the arm 160 breaks the toggle 152, 154 releasing the upper gripper and at the same time, effects the release of the one-way clutch by depressing the arm 178. Release of the one-way clutch permits the upper gripper assembly to move back to the position shown in Fig. 18 under the urging of the spring 156.

The side and toe grippers are released through the action of a trip 414 (Fig. 16) which is pivoted on the lower end of the lever 286 and acts upon a latch-controlling bell-crank lever 416. When the lever 286 is moved in a counterclockwise direction to raise the upper shaping form, the trip 414 snaps over the end of the lever 416, and upon its return movement, it rotates the lever 416 and thereby effects the release of the latches 264, 265 through a linkage system, which will now be described. The bell-crank lever 416 is connected by a link 418 (Figs. 1 and 18) to an arm 420 of a three-armed lever. A second arm 422 20 of the three-armed lever has a shoulder formed thereon which lies behind the top edge of the latch 264, while the third arm 424 is connected by a link 426 to a second lever 428 which controls the latch 265. Upon the return movement of the lever 286, which takes place during the lowering of the form, the trip 414 strikes a finger 415 on the bell-crank lever 416, causing the same to move in a counterclockwise direction and raise the link 418. This movement of the link 418 30 causes a corresponding movement of both the three-armed lever and the lever 428 which moves the latches 264, 265 from beneath the grip-operating levers 230, 252. Release of the grip-operating levers allows the springs 432, 433 to move the levers in a clockwise direction and thereby cause the opening of the gripper jaws. As the lever 286 approaches its forward position (Fig. 18), the spring 342, which is a combined tension and compression spring, rotates the toe gripper assembly in a clockwise direction, releasing the longitudinal pull on the upper, and opening the jaws 347, 349.

When the cam 280 reaches the position shown in Fig. 18, the driving mechanism is automatically disconnected, and as the grippers have all been released, the operator can remove the assembled upper from the machine. At this time the parts, with the exception of the gripping finger 90 will be in the position shown in Fig. 18. 50 The gripping finger 90 will be held in the position shown in Fig. 16 by the latch 360 which is not released until another counter has been placed on the support 88 during the counter transfer phase of the next assembling operation.

Transmission and clutch operating mechanism

The shaft 94 which rotates the cams 92 and 280 is driven by an electric motor 440 (Fig. 1) mounted on a platform formed on the rear portion of the base 10. The motor 440 is connected with the shaft 94 by a transmission system comprising a driving shaft 442 (Fig. 16), a driven shaft 444 (Fig. 11), and the clutch 96. The driving shaft 442 is coupled to the motor by a belt

446 (Fig. 1) which passes over a pulley 448 fast to the motor shaft and a pulley 450 which is connected to the driving shaft. The driving shaft is connected with the driven shaft by intermeshing gears 454, 455 which are connected, respectively, to the driving and driven shafts (Fig. 3), and the driven shaft is, in turn, connected with the clutch by a worm 456 which meshes with a worm wheel 457 on one member of the clutch 96. The clutch 96 is of the cyclic-operated type described and claimed in United States Letters Patent No. 2,221,875, granted November 19, 1940, on my application for improvements in Driving mechanisms. Only so much of the clutch structure will be described as is necessary to give an understanding of its operation in its present environment.

The clutch includes a pair of connected angularly-spaced dogs 458, 460 (Fig. 1) which disconnect the clutch when either of the dogs strikes a stop member 462. The stop member 462 is urged into the path of the dogs by a spring 464 and is moved out of that path by a shoulder 473 on a bar 468 (Fig. 17) which engages a shoulder 463 on the latch. The rear end of the bar 468 is pivoted to the forked head of a rod 466 which is slidably mounted in the front wall of the clutch housing. The rear end of the rod is fastened to a plate 467 which abuts the hand lever 274 and carries at its lower end a pin 465 which extends into a recess in the casing and is urged to the left, as viewed in Fig. 1, by a spring 469 which is confined in the bottom of the recess. The pin 465, due to the action of the spring 469, tends to move the bar 468 to the left, as viewed in Fig. 1, and in addition, it prevents the rod 466 and the bar 458 from rotating and thereby moving out of proper relation to the other parts of the clutch.

At the beginning of an assembling operation, the dog 458 will be in engagement with the stop member 462 and will be displaced sufficiently to disconnect the clutch. To start the first part of the power cycle of the machine, the operator moves the hand lever 274 in a clockwise direction, as viewed in Fig. 1, thereby displacing to the right the pin 466 and the bar 468. This movement of the bar carries the stop 462 out from under the dog 458, thereby permitting the clutch members to become engaged and rotate the cam shaft 94 until the stop 462, which has meanwhile been disconnected from the bar 468, engages the dog 460. The disengagement of the stop member 462 from the bar is effected by a cam 470 on the periphery of one of the clutch members where it is disposed in the path of a projection 472 on the bar so that when the clutch is rotated, the cam 470 strikes the projection 472 and moves the bar downwardly a sufficient distance to move the bar shoulder 473 below the stop shoulder 463 and allow the spring 464 to return the stop to the position shown in Fig. 1. When the bar is moved downwardly to its inoperative position by the cam 470, it is held in that position by a latch 474.

The latch 474 is controlled by the treadle 240 which operates the tip line grippers and is released by depressing that treadle to close the gripper jaws, thereby insuring that the proper stresses will be set up in the upper when the clutch is operated a second time to move the form into the upper. The connections between the latch 474 and the treadle mechanism consist of a bell-crank lever 476 (Fig. 1), one arm of which is connected by a link 478 to the yoke 246 of the tip line gripper linkage and the other arm

to a crank arm 480 by a rearwardly extending link 482 (Fig. 19). The crank arm 480 is fastened to one end of a shaft 484 which extends transversely of the head 12 and is connected at its other end (Fig. 14) to the latch 474. The link 482 is connected to the crank arm 480 by a loose connection which permits the latch to move rearwardly with the bar 468 without releasing the same in the event that the hand crank 274 is inadvertently operated before the grippers are properly adjusted. The connection between the link 482 and the crank arm 480 consists of a sleeve 486 which is pivoted to the crank arm and is slidable on the link between a collar 488 formed on the link and a spring 490 which surrounds the rear end of the link and is held thereon by a nut 492. When the tip grippers are closed by operating the treadle 240, downward movement of the yoke 246 causes a rearward displacement of the link 482 which disengages the latch 474 from the bar 468. When released, the bar moves up into operative engagement with the stop 462 so that the operator can forthwith release the second dog 460 by again operating the hand lever 274 and effect the second part of the power cycle of the machine.

Operation of the machine

In practicing the method of assembling shoe uppers and counters in accordance with the present invention, the operator first attaches a counter to the counter carrier in the cement unit and dips it into the quick-setting cement contained in the pot 14. After the counter has been dipped and the counter carrier moved up to its raised position shown in Fig. 11, the lever 274 is operated to start the first part of the power cycle of the machine. During this cycle the counter is gripped by the needles 70 on the gripping levers 50, 52 and is transferred, flange down, to the assembling support 58, and as the counter is placed on the support 58, the latch 360 is depressed by the projection 356 on the cam 280 and is moved downwardly out of the path of the plate 316. Release of the plate 316 allows the spring 320 to move it rearwardly, as viewed in Fig. 18, thereby causing the gripping finger 90 to move downwardly and rearwardly into engagement with the counter flange and clamp it against the support 58. Shortly after the finger 90 engages the counter flange, the gripping levers 50, 52 are released and the counter transfer mechanism returned to a position in the rear of the counter carrier in the cement pot. The machine is then automatically stopped by the engagement of the stop 462 with the dog 460.

The operator now connects the back seam grippers 120, 124 to the rear portion of the upper, locates the margin of the upper properly with respect to the shank and tip line grippers and treadles the same, and then places the toe end of the upper between the jaws of the toe gripper. The operator next smooths the lining against the inside of the counter by the use of a convenient tool such as the blade 272, and after the lining has been smoothed, he again operates the lever 274, causing the machine to go through the second part of the power cycle of the machine. During this cycle, the form 270 is moved up into the upper, stretching the same against the pull of the grippers and thereby duplicating the pulling over and side lasting stresses and causing the upper, lining and counter to be shaped about the heel end of the form and be bonded together under conditions which are similar to those to

which they will be subjected in the subsequent lasting operation. As the form moves into the upper, the margin of the heel seat face contacts the lining at a point between the top edge of the counter and the counter flange, and wipes the lining downwardly as it moves toward the flange. As the heel seat face of the form approaches the counter flange, the bottom portion of the lining which overlies the counter flange is stretched inwardly beneath the bottom of the form by the bar 366 and the levers 368, 370 so that the downwardly moving heel portion of the form will lay the lining smoothly against the counter flange. The final straightening of the toggle 286, 292 presses the heel end of the form against the support 58 with considerable force, thereby pressing down the gathers which formed about the head of the clamping finger 90.

As the form moves into the upper, the clamping finger 90 is moved out of engagement with the counter and a short distance to the left, as viewed in Fig. 16, where it is located within an opening 271 formed in the heel portion of the form 270. The clamping finger is held in this position until an appropriate time during the next counter transfer operation by the latch 364. The form 270 is allowed to remain in the position shown in Fig. 16 a short interval while the quick-setting cement forms an initial bond between the shaped lining, counter and upper, after which the continued operation of the machine causes the form to move from that position downwardly to the position shown in Fig. 18. As the form is moved out of the upper, the trip 408 releases the back seam grippers, and the trip 414 releases the treadles which are raised by the springs 431, 432, thereby releasing the shank and tip line grippers, the toe gripper meanwhile being released by the clockwise movement of the lever 286. The assembled upper can now be taken from the machine and a new series of operations started. If desired, a second counter may be dipped in the cement and allowed to drain while the second cycle of machine operations is taking place and the molded upper removed from the machine.

Having thus described my invention, what I claim as new and desire to secure by Letters Patent of the United States is:

1. That method of making shoes which comprises immersing a counter in fluid cement, lifting the counter into a predetermined draining position, transferring the counter from the draining position to an assembling position, positioning a lined upper relatively to the supported counter, holding the rear part of the upper by its top margin, and while the upper is so held, wiping the rear part of the lining toward the counter flange.

2. That method of making shoes which comprises immersing a counter in fluid cement, lifting the counter into a predetermined draining position, transferring the counter from the draining position to an assembling position, positioning an upper in predetermined relation to the counter, gripping the opposite ends of the back seam of the upper, and forcing a form into the upper to shape the upper while it is so held.

3. That method of assembling and shaping uppers which comprises assembling an upper and a counter, stretching the assembled upper in a lengthwise direction and, while the upper is under lengthwise tension, exerting pulls on the lasting margin at selected side portions to cause the heel portion of the assembled upper to set with the upper under lengthwise and heightwise

stresses similar to those to which it will be subjected during the subsequent lasting operation.

4. That method of assembling and shaping uppers which comprises assembling an upper and a counter, supporting the upper at the heel end, holding the lasting margin of the upper in opposite shank portions, in the opposite tip line portions and at the toe end, stretching the upper in a lengthwise direction and concomitantly stretching the upper in a heightwise direction to cause the heel portion of the assembled upper to set with the upper under lengthwise and heightwise stresses similar to those to which it will be subjected during the subsequent lasting operation.

5. That method of assembling and shaping uppers which comprises assembling an upper and a counter, supporting the upper at the heel end, holding the lasting margin of the upper in opposite shank portions, opposite tip line portions and at the toe end, stretching the upper in a lengthwise direction, inserting a form into the upper, and imparting relative heightwise movement to the form and the upper to cause the heel portion of the upper to set with the upper under lengthwise and heightwise tension similar to that to which it will be subjected during the subsequent lasting operation.

6. That method of assembling and shaping uppers and flanged counters off the last which comprises assembling an upper and a counter, supporting the rear portion of the assembled upper, stretching the upper in a lengthwise direction, inserting a form into the upper with a combined heightwise and heelward movement, stretching the marginal portion of the lining adjacent the counter flange inwardly beneath the heel portion of the form, and urging the forepart of the form upwardly from the lasting margin and the heel portion of the form rearwardly and downwardly to lay the lining smoothly over the counter flange and to shape the heel end of the upper.

7. That method of assembling an upper and a molded counter which comprises mechanically supporting a cement-treated counter by its sole attaching margin, positioning a lined upper in determinate relation to the counter heightwise thereof, supporting the heel portion of the upper, stretching the upper in a lengthwise direction and while the upper is under lengthwise tension exerting pulls on the lasting margin at selected points to cause stresses in the upper similar to those to which it will be subjected during the lasting operation, and pressing the upper, counter, and lining together while subjected to these stresses to cause the heel portion of the counter to set under lasting conditions.

8. That method of assembling and shaping shoe uppers which comprises supporting the heel end of an assembled upper, gripping the upper in the opposite shank portions, inserting a form in the upper and imparting relative heightwise movement to the form and the gripped portion of the upper to set up in the upper stresses similar to side lasting stresses, and concomitantly imparting relative lengthwise movement to the form and the upper to shape the heel portion of the upper about the heel end of the form while the upper is subjected to the stresses.

9. That method of assembling and shaping shoe uppers which comprises supporting the heel end of an assembled upper, holding the upper in opposite shank portions, inserting a form in the upper and urging the form upwardly to set

up in the upper stresses similar to side lasting stresses and at the same time moving the form rearwardly to shape the heel portion of the upper while it is subjected to the side lasting stresses.

5 10. That method of assembling and shaping shoe uppers which comprises supporting the heel end of an assembled upper, holding the lasting margin of the upper adjacent the opposite ends of the tip line and at the toe end, inserting a form in the upper and imparting relative heightwise and lengthwise movement to the form and the upper to set up stresses in the upper similar to pulling over stresses and to shape the heel end of the upper while it is subjected to those stresses.

15 11. That method of assembling and shaping shoe uppers which comprises supporting the heel end of an assembled upper, holding the lasting margin of the upper adjacent the opposite ends of the tip line and at the toe end, imparting relative movement to the grippers and the heel end support to stretch the upper in a lengthwise direction, inserting a form into the upper and urging the toe end of the form upwardly to set up in the upper stresses similar to pulling over stresses, and moving the heel end of the form rearwardly and downwardly to wipe the upper and shape its heel end while subjected to the stresses.

20 30 12. That method of assembling and shaping shoe uppers which comprises supporting a cement-treated counter by its sole attaching flange, positioning a lined upper in determinate relation to the counter heightwise thereof and supporting the upper in that position, smoothing the lining against the inner surface of the counter, stretching the marginal portion of the lining adjacent to the sole attaching counter flange inwardly above the flange, and moving a form downwardly against the stretched lining to lay it smoothly over the flange.

35 40 13. That method of assembling and shaping shoe uppers which comprises supporting a cement-treated counter by its sole attaching flange, positioning a lined upper in determinate relation to the counter heightwise thereof and supporting the upper in that position, smoothing the lining against the inner surface of the counter, collecting the excess material in the marginal portion of the lining in gathers over the heel end of the counter flange, and moving a form into the heel portion of the upper to press the gathers against the counter flange.

45 55 60 65 14. That method of assembling and shaping shoe uppers which comprises supporting a cement-treated counter by its sole attaching flange, positioning a lined upper in determinate relation to the counter heightwise thereof and supporting the upper in that position, smoothing the lining against the inner surface of the counter, collecting the excess material in the marginal portion of the lining in gathers over the heel end of the counter flange, stretching the marginal portion of the lining adjacent to the counter flange inwardly above the counter flange, and moving a form rearwardly and downwardly into the heel end of the upper to wipe the lining heightwise of the upper and to press the marginal portion of the lining against the counter flange.

70 75 15. A machine for shaping the heel end of an assembled upper off the last comprising means for supporting an assembled upper, an upper shaping form, and means for moving the shaping form into and out of the supported upper.

16. A machine for shaping the heel end of an assembled upper off the last comprising means for supporting an assembled upper, said means including devices for engaging and gripping the opposite end portions of the back seam, an upper shaping form, and means for moving the upper shaping form into and out of the supported upper.

17. A machine for shaping the heel end of an assembled upper off the last comprising means for supporting an assembled upper, said means including devices for gripping the opposite end portions of the back seam, means for urging the devices away from each other after they engage the upper to stretch the heel portion of the upper in a heightwise direction, an upper shaping form, and means for moving the form into and out of the supported upper.

18. A machine for shaping the heel end of an assembled upper off the last comprising means for supporting an assembled upper, said means including grippers arranged to engage the lasting margin in the opposite shank portions of the upper, an upper shaping form adapted for movement into the supported upper, and means for causing relative heightwise movement between the shank grippers and the shaping form to set up in the upper stresses similar to side lasting stresses.

19. A machine for shaping the heel end of an assembled upper off the last comprising means for supporting an assembled upper, said means including grippers arranged to engage the lasting margin in the opposite shank portions of the upper, an upper shaping form, and means for moving the upper shaping form into and heightwise of the upper to stretch the same against the resistance of the shank grippers thereby causing stresses similar to side lasting stresses.

20. A machine for shaping the heel end of an assembled upper off the last comprising means for supporting an assembled upper, said means including grippers arranged to engage the lasting margin adjacent the opposite ends of the tip line, an upper shaping form, and means for moving the form into and out of the supported upper, said last-named means being arranged to cause the forepart of the upper to be stretched against the resistance of the tip line grippers thereby duplicating in the upper the pulling over stresses.

21. A machine for shaping the heel end of an assembled upper off the last comprising means for supporting an assembled upper, a gripping device arranged to grasp the lasting margin at the toe end of the upper, an upper shaping form arranged for movement into and out of a supported upper, and means for moving the form into the upper and for causing the toe gripper to grasp the lasting margin and exert a longitudinal pull in the upper as the form is being moved into the same.

22. A machine for shaping the heel end of an assembled upper off the last comprising means for supporting an assembled upper, said means including gripping devices arranged for engagement with the lasting margin of the upper adjacent the opposite ends of the tip line and at the toe end, an upper shaping form arranged for movement into and out of the supported upper, and means for moving the form into the upper, said means being arranged to urge the forepart of the form in a heightwise direction against the resistance of the tip line grippers

and to cause the toe end gripper to stretch the upper in a lengthwise direction.

23. A machine for shaping the heel end of an assembled upper and counter off the last comprising means for supporting an assembled upper and counter, an upper shaping form, and cam-controlled means for moving the form into and out of the supported upper.

24. A machine for shaping the heel end of an assembled upper off the last comprising means for supporting an assembled upper, said means including grippers arranged to engage the heel end of an upper and the lasting margin at the toe end thereof, an upper shaping form, a cam-controlled linkage system for moving the form into and out of the supported upper, and means operated by the linkage system as the form is being moved into the upper to cause relative movement between the toe and heel grippers thereby to exert a longitudinal pull on the upper.

25. A machine for shaping the heel end of an assembled upper off the last comprising means for supporting an assembled upper, said means including grippers arranged to engage the heel end of an upper and the lasting margin at the toe end thereof, an upper shaping form, a power-operated linkage system, and means controlled by the linkage system for urging the toe gripper away from the heel grippers as the form is being moved into the upper thereby to pull the upper in a lengthwise direction.

26. A machine for shaping the heel end of an assembled upper off the last comprising means for supporting an assembled upper, an upper shaping form, and a power-operated linkage system for moving the form heightwise into an upper and rearwardly thereof into the heel end of the same.

27. A machine for shaping the heel end of an assembled upper off the last comprising means for supporting an assembled upper, an upper shaping form arranged for movement into and out of the supported upper, and a power-operated linkage system for moving the form heel first into the upper and also heightwise thereof to stretch the upper into approximately the shape that it will assume when lasted.

28. A machine for shaping the heel end of an assembled upper off the last comprising means for supporting an assembled upper, an upper shaping form arranged for movement into and out of a supported upper, said form being supported in its rear portion by a pivoted arm and in its forepart by a toggle, means for moving the pivoted arm rearwardly to carry the heel portion of the form into the upper, and means for straightening the toggle to force the forepart of the form heightwise into the supported upper and firmly to press the heel portion of the form into the heel end of the upper.

29. A machine for operating on shoe uppers comprising a pair of grippers arranged to engage and grip an upper at opposite ends of the back seam, an upper shaping form, means for moving the upper shaping form into and out of the upper, and means for automatically releasing the grippers as the upper shaping form is moved out of the upper.

30. A machine for operating on shoe uppers comprising grippers arranged to engage the lasting margin of an upper adjacent to the opposite ends of the tip line and at the toe end, an upper shaping form, power-operated means for moving the upper shaping form into and out of the

upper, and means controlled by the power-operated means for automatically releasing the grippers as the form is moved out of the upper.

31. A machine for operating on shoe uppers comprising grippers arranged to engage an upper at opposite ends of the back seam and the lasting margin of the upper in the opposite shank portions, at opposite ends of the tip line and at the toe end thereof, an upper shaping form, power-operated means for moving the form into and out of the supported upper, and means controlled by the power-operated means for automatically releasing all the grippers as the form is moved out of the upper.

32. A machine for shaping the heel end of an assembled upper off the last comprising means for supporting an assembled upper, said means including grippers arranged to engage the lasting margin of the upper in the opposite shank portions and adjacent the opposite ends of the tip line, treadles for closing said grippers, latches for holding said grippers closed, an upper shaping form, power-operated means for moving said form into and out of the upper, and latch-releasing means controlled by said power-operated means and arranged to release the gripper latches as the form is moved out of the upper.

33. A machine for shaping the heel end of an assembled upper off the last comprising upper holding means arranged for engagement with predetermined portions of an assembled upper, treadle-operated means for connecting the holding means to the upper, an upper shaping form, power-operated means for moving the shaping form into the upper, and an interlock between the treadle-operated means and the power means arranged to prevent operation of the power-operated means until the holding means has been connected with the upper.

34. A machine for shaping the heel end of an assembled upper off the last comprising means for supporting an upper, said means including grippers arranged to engage the lasting margin of an assembled upper at predetermined points, treadle-operated means for causing the grippers to take hold of the upper, an upper shaping form arranged for movement into the supported upper, power-operated means for moving the shaping form into the upper and urging the upper away from the grippers to set up in the upper stresses similar to those to which it will be subjected during the subsequent lasting operation, and an interlock between the treadle-operated means and the power-operated means arranged to prevent operation of the power-operated means until the grippers have been connected to the upper.

35. A machine for shaping the heel end of an assembled upper off the last comprising grippers arranged to take hold of the lasting margin of the upper in the opposite shank portions and adjacent to the opposite ends of the tip line, treadle-operated means for controlling the grippers, an upper shaping form, power-operated means for moving the shaping form into the upper to stretch the same and set up stresses similar to the lasting stresses, and an interlock between the treadle-operated means and the power-operated means arranged to prevent operation of the power-operated means until the grippers have been connected to the upper.

36. A machine for assembling shoe uppers off the last comprising means for supporting a loose counter, means for holding the back part of a lined upper in determinate relation to the sup-

ported counter, and means for holding the lasting margin of the upper in the opposite shank portions and adjacent to the opposite ends of the tip line.

37. A machine for assembling flanged counters and uppers off the last comprising a counter support, a counter holder arranged to clamp the counter flange against the support, means for holding the back part of a lined upper in determinate relation to the supported counter, and grippers arranged for engagement with the lasting margin of the upper in the opposite shank portions and adjacent to the opposite ends of the tip line.

38. A machine for assembling flanged counters and uppers comprising a counter support, a member for clamping the flange in the heel end of the counter against the counter support, and means for holding the back part of a lined upper in determinate relation to the supported counter, said clamping member having a head shaped to cause the excess material in the marginal portion of the lining to collect over the heel end of the counter flange.

39. A machine for assembling flanged counters and uppers comprising a counter support, a member for clamping the flange in the heel end of a counter against the support, and means for holding the back part of a lined upper in determinate relation to the supported counter, said clamping member having a knob-shaped head arranged to engage beneath the marginal portion of the lining and cause the excess lining material to collect about the clamping member.

40. A machine for assembling flanged counters and uppers comprising a counter support, a member for clamping the flange at the heel end of a counter against the support, means for holding the back part of a lined upper in determinate relation to the supported counter, said clamping member having a head shaped to cause the excess material in the marginal portion of the lining to collect in folds over the flange at the heel end of the counter, an upper shaping form, and means for moving the form into the upper, said means including a toggle arranged to press the heel end of the form against the folds in the lining material.

41. A machine for assembling and shaping flanged counters and uppers comprising a counter support, means for positioning a lined upper in determinate relation to a counter on the support, an upper shaping form arranged for movement into and out of the supported upper, means for moving the heel portion of the form rearwardly and downwardly into the heel end of the upper, and means for stretching the marginal portion of the lining opposite the side walls of the counter inwardly beneath the downwardly moving heel end of the form whereby said lining is laid smoothly over the counter flange.

42. A machine for assembling and shaping flanged counters and uppers comprising a counter support, means for positioning a lined upper in determinate relation to a counter on the support, an upper shaping form, means for moving the heel portion of the form rearwardly and downwardly into the heel end of the upper, and means for stretching the marginal portion of the lining opposite to the side walls of the counter inwardly beneath the downwardly moving heel end of the form, said stretching means comprising yieldable members underlying the marginal portion of the lining adjacent to the side walls of the counter, and a member arranged for move-

ment in advance of the form to grip the lining against the yieldable members and stretch the lining inwardly beneath the heel end of the form.

43. A machine for assembling and shaping molded counters and uppers comprising a counter support, a counter holder for positioning a counter on said support, upper supporting means arranged to position a lined upper in determinate relation to the supported counter, an upper shaping form, and means for moving said form into and out of the supported counter.

44. A machine for assembling and shaping molded counters and uppers comprising a counter support, a counter holder for positioning a counter on said support, upper supporting means arranged to position a lined upper in determinate relation to the supported counter, an upper shaping form, means for moving the upper shaping form into and out of the upper, and means associated with form-operating means for moving the counter holder out of the path of the upper shaping form as the form moves into the upper.

45. A machine for assembling and shaping molded counters and uppers comprising a counter support, a counter holder for positioning a counter on said support, upper supporting means arranged to position a lined upper in determinate relation to the supported counter, an upper shaping form having a recess in its rear portion, power-operated means for moving the shaping form into and out of the upper, and means controlled by said power-operated means for moving said counter holder away from the counter and into register with the recess in the form as the form moves into the upper.

46. A machine for assembling and shaping molded counters and uppers comprising a counter support, a counter holder for positioning a counter on the support, said counter holder being arranged for movement between an operative position and an inoperative position, a latch for retaining said counter holder in its inoperative position, upper supporting means arranged to position a lined upper in determinate relation to the supported counter, an upper shaping form, and means for moving the shaping form into the supported counter, said form-moving means being arranged to move the counter holder to its inoperative position and latch it in that position as the shaping form is moved into the counter.

47. A machine for assembling and shaping molded counters and uppers comprising a counter support, means for cement-treating a counter and placing the counter on the support, means for holding the counter on the support, and upper supporting means arranged to position a lined upper in determinate relation to the supported counter.

48. Counter handling means comprising means for dipping a counter in cement, a counter support, and means for transferring a counter from the dipping means to the support.

49. A machine for assembling and shaping molded counters and uppers comprising means for dipping a counter in cement, a counter support, means for transferring a counter from the dipping means to the support, means for holding the counter on the support, and upper supporting means arranged to position a lined upper in determinate relation to the supported counter.

50. A machine for assembling and shaping molded counters and uppers comprising means for dipping a counter in cement, a counter support, means for transferring a cemented counter from the dipping means to the support, clamping

means for holding the counter on the support, upper supporting means arranged to position a lined upper in determinate relation to the supported counter, an upper shaping form, and means for moving said form into the supported upper.

51. A machine for assembling and shaping molded counters and uppers comprising means for dipping a counter in cement, a counter support, means for transferring a cemented counter from the dipping means to the support, counter holding means arranged for movement between an inoperative position and a position where it holds the counter on the support, a latch for retaining the holding means in its inoperative position, and means for releasing the latch when a cement-treated counter is placed on the support.

52. A machine for assembling and shaping molded counters and uppers comprising means for dipping a counter in cement, a counter support, counter transfer means arranged to move a cemented counter from the dipping means to the support, and a counter holding member arranged for movement between an operative and an inoperative position, said counter holding member having a jaw arranged to clamp the marginal portion of a counter against the counter support when the counter holding member is in its operative position.

53. Counter holding means comprising a horse-shoe-shaped support arranged for engagement with the marginal portion of a counter, and a clamping finger arranged for movement between an inoperative position and a position where it clamps the marginal portion of a counter against the support.

54. Counter holding means for flanged counters comprising a substantially U-shaped support arranged for engagement with the under side of a counter flange, a counter clamping member arranged for movement between an inoperative position and a position where it clamps the counter flange against the support, and a latch for holding the clamping member in its inoperative position.

55. A machine for assembling and shaping molded counters and uppers comprising means for dipping a counter in cement, a counter support, counter transfer means arranged to move a cement-treated counter from the dipping means to the support, counter holding means arranged for movement between an inoperative position and a position where it holds the cement-treated counter on the support, a latch for retaining the counter holding means in its inoperative position, power means for operating the counter transfer means, and means controlled by the power means for releasing the latch as the counter is placed on the support.

56. In an assembling machine, a counter support, counter transfer means for moving a counter from a remote position to the counter support, counter holding means arranged for movement between an inoperative position and a position where it holds a counter on the support, a latch for retaining the counter holding means in its inoperative position, power means for operating the counter transfer means, and means controlled by the power means for releasing the latch as the counter is placed on the support.

57. A machine for assembling and shaping flanged counters and uppers comprising means for dipping a counter in cement, a counter support, counter transfer means arranged to move a cement-treated counter from the dipping

means to the support, a counter holding member arranged for movement between an inoperative position and a position where it clamps the counter flange against the support, a latch for retaining the counter holding member in its inoperative position, upper supporting means arranged to position a lined upper in determinate relation to the supported counter, an upper shaping form arranged for movement into and out of a positioned upper, and power means for operating the transfer mechanism and the upper shaping form, said power means being arranged to move the counter holding member away from the support and latch it in an inoperative position when the shaping form is moved into the upper and to release the holding latch when a cement-treated counter is placed on the support by the transfer mechanism.

58. A counter carrier arranged to immerse a counter in fluid cement, said counter carrier having a plate shaped to fit within the side walls of the counter and prevent the counter from tilting when immersed in the cement.

59. A counter carrier arranged to immerse a counter in fluid cement, the counter carrier comprising a plate shaped to fit within the side walls of the counter and a narrow flange depending from the plate, said flange having clamping means arranged to engage the heel end of the counter and position the sole attaching portion of the counter opposite to the plate.

60. A counter carrier arranged to immerse a molded counter in fluid cement, said carrier having a plate shaped to fit within the side walls of a molded and flanged counter and prevent the same from tilting relatively to the carrier, and means for moving the counter carrier in a heightwise direction to immerse a counter and to raise the counter to a dripping position, said means being arranged to hold the carrier in a substantially vertical position during its heightwise movement whereby the side walls of the counter can be coated with cement without applying cement to the flange of the counter.

61. A counter carrier having a plate shaped to fit within the side walls of a molded counter, and means for moving the counter carrier in a heightwise direction to immerse a counter in fluid cement and to raise it to a dripping position, said means including parallel plate-supporting links arranged to maintain the counter carrier in a substantially vertical position throughout its heightwise movement.

62. Mechanism for processing counters comprising means for cement-treating a counter, a counter support, and counter transferring means for moving a cement-treated counter from the cement-treating means to the counter support.

63. Mechanism for processing counters comprising means for cement-treating a counter, a counter support, counter transferring means for moving the cement-treated counter from the cement-treating means to the counter support, said counter transferring means comprising a gripping device arranged to lift the counter from the cement-treating means and place it on the counter support, and means for moving the counter gripping device between the cement-treating means and the counter support.

64. Mechanism for processing counters comprising means for applying cement to a counter, a counter support, counter transferring means for moving the cement-treated counter from the cement applying means to the counter support,

said counter transferring means comprising a counter gripping device, and power-operated means for moving the counter gripping device in an arcuate path between the cement applying means and the counter support.

65. Mechanism for processing counters comprising a counter carrier arranged to immerse a molded counter in fluid cement, said counter carrier having a plate shaped to fit within the side walls of the counter, a counter support, counter gripping means mounted on a member which is arranged for movement between the counter carrier and the counter support, and power-operated means for moving the member away from the counter carrier with a movement having rearward and heightwise components to withdraw the molded counter from the support without appreciably bending the molded side walls of the counter.

66. Mechanism for processing counters comprising a counter carrier arranged to immerse a flanged counter in fluid cement, said carrier comprising a plate shaped to fit within the counter flange and a member extending from the plate,

25 said member having holding means arranged to engage the marginal portion of the rear end of the counter and position the counter flange opposite to the plate, a counter support spaced from the counter carrier, and counter transfer means for moving the cement-treated counter from the counter carrier to the counter support, said transfer means comprising a counter gripping member, and means for moving the counter gripping member away from the counter carrier with a movement having rearward and arcuate components which cause the counter carrier to pass through the wide foot-receiving opening in the counter as the counter is removed from the carrier.

40 67. Mechanism for processing counters comprising means for applying cement to a counter, a counter support, counter transferring means for moving the cement-treated counter from the cement applying means to the counter support,

45 said counter transferring means comprising an oscillatable arm, counter gripping members mounted on said arm for movement toward and away from each other, and a power-driven shaft for swinging said arm between the cement applying means and the counter support.

68. Mechanism for processing counters comprising means for applying cement to a counter, a counter support, counter transferring means for moving the cement-treated counter from the cement applying means to the counter support,

55 said counter transferring means comprising an oscillatable arm, counter gripping members mounted on said arm for movement toward and away from each other, a power-driven shaft for operating said arm, and power-controlled means for causing the gripping members to take hold of the counter at the cement applying means and to release the counter when it is placed on the counter support.

60 69. Mechanism for processing counters comprising means for applying cement to a counter, a counter support, counter transferring means for moving the cement-treated counter from the cement applying means to the counter support, said counter transferring means comprising an os-

70 cillatable arm, counter gripping means mounted on said arm, a shaft connected with said arm, said shaft being arranged for axial and rotary movements, a reciprocating member for operating the gripping means, and power means for

75

operating said shaft and said reciprocating member.

70. Mechanism for processing counters comprising means for applying cement to a counter, a counter support, counter transferring means for moving the cement-treated counter from the cement applying means to the counter support, said counter transferring means comprising counter gripping members, a shaft for moving said counter gripping members in an arcuate path between the cement applying means and the counter support, said shaft being mounted for rotary movement and limited axial movement, a control member for causing the counter gripping members to engage and release the counter, said control member being connected to a rod which is frictionally coupled with said shaft, and power-operated means for moving said rod in the direction of its axis during the rotation of the shaft to cause an axial movement of the shaft, said power-operated means being arranged to move the rod a limited extent after the shaft has reached its limit of axial movement to open and close the gripping members.

71. A machine for assembling and shaping molded counters and uppers off the last comprising a counter carrier arranged to immerse a molded counter in fluid cement, a counter support spaced from the counter carrier, counter transfer means arranged to remove the cement-treated counter from the counter carrier without appreciably spreading the side walls of the counter and place it on the counter support, means for supporting a lined upper in determinate relation to the counter on the counter support, an upper shaping form, and means for moving the heel end of the upper shaping form heightwise of the supported upper through the bottom of the upper and thence rearwardly and downwardly into the heel end of the upper.

72. In a machine for operating on shoe uppers, a member for engaging the lasting margin of the upper in the region of the back seam, a gripper for engaging the upper in the region of the opposite end of the back seam, means for imparting relative movement to the member and the gripper in order to tension the heel end of the upper, and locking means associated with the member and the gripper for holding the heel end of the upper under tension.

73. In a machine for operating on shoe uppers, a member for engaging the lasting margin of the upper in the region of the back seam, a gripper for engaging the upper in the region of the opposite end of the back seam, means for urging the gripper in a heightwise direction away from said member to tension the heel end of the upper, and a detent associated with the gripper and arranged to prevent movement of the gripper toward the member while permitting the gripper to move away from the member.

74. In a machine for operating on shoe uppers, a member for engaging the lasting margin of the upper in the region of the back seam, a gripper for engaging the upper in the region of the opposite end of the back seam, said gripper being arranged for movement between an inoperative position and an upper engaging position, means for urging the gripper away from the member in order to tension the heel end of the upper, and a detent associated with said means and arranged to prevent movement of the gripper toward said member.

75. In a machine for operating on shoe uppers, a member for engaging the lasting margin of the

upper in the region of the back seam, a gripper for engaging the upper in the region of the opposite end of the back seam, a swingable support for the gripper arranged to move the gripper between an inoperative position and an upper engaging position, means for urging the gripper in a heightwise direction away from said member to tension the heel end of the upper, and a one-way clutch associated with the swingable support and arranged to permit movement of the gripper away from said member while preventing its movement toward the member.

76. In a machine for operating on shoe uppers, a member for engaging the lasting margin of an upper in the region of the back seam, a gripper for engaging the upper in the region of the opposite end of the back seam, means for urging the gripper in a heightwise direction away from said member to tension the heel end of the upper, a detent associated with the gripper and arranged to prevent movement of the gripper toward the member while permitting the gripper to move away from said member, and means for rendering the detent inoperative when the gripper is not in engagement with the upper.

77. In a machine for operating on shoe uppers, a member for engaging the lasting margin of an upper in the region of the back seam, a gripper for engaging the upper in the region of the opposite end of the back seam, said gripper being arranged for movement between an inoperative position and an upper engaging position, a detent associated with the gripper and arranged to prevent movement of the gripper toward said member while the gripper engages the upper, and resilient means arranged to urge the gripper in a heightwise direction away from the member to tension the heel end of the upper and also to clamp the gripper members against the upper and to render the detent effective.

78. In a machine for operating on shoe uppers, a member for engaging the lasting margin of an upper in the region of the back seam, a gripper for engaging the opposite end of the back seam, a swingable support for the gripper arranged to move the gripper between an inoperative position and an upper engaging position, and a spring arranged to urge the gripper in a heightwise direction away from said member to tension the heel end of the upper, the spring being connected to the gripper support so that it is energized as the gripper is moved to the upper engaging position.

79. In a machine for operating on shoe uppers, means for supporting an upper, a toe gripper arranged for movement in a direction lengthwise of the supported upper, side grippers arranged for engagement with the lasting margin on opposite sides of the upper, means for moving the toe gripper lengthwise of the upper, and means controlled by the toe gripper for urging the side grippers in the direction of movement of the toe gripper.

80. In a machine for operating on shoe uppers, means for supporting an upper, a toe gripper arranged for movement in a direction lengthwise of the supported upper, side grippers arranged for movement in a direction lengthwise of the supported upper, and means for connecting the toe gripper with the side grippers.

81. In a machine for operating on shoe uppers, means for supporting an upper, a toe gripper arranged for movement in a direction lengthwise of a supported upper, movably-mounted side grippers arranged for engagement with the lasting

margin of the upper adjacent to the opposite ends of the tip line, and resilient means for connecting the toe gripper with the side grippers whereby movement of the toe gripper will be transmitted to the side grippers.

82. In a shoe machine, means for supporting an unattached upper, a form arranged for movement into the supported upper through its bot-

tom opening, said form including an instep portion arranged for movement relatively to the remainder of the form and resilient means for urging the instep portion away from the heel end of the form, and means for moving the form into and out of the upper.

ROBERT H. LAWSON.
